COOKING STOVE

John Wesley Buckingham, London, England, assignor to
The Jackson Electric Stove Co. Limited

Application June 23, 1953, Serial No. 25,621

Claims priority, application Great Britain April 23, 1953

Term of patent 14 years

(Cl. D81—4)

To all whom it may concern:

Be it known that I, John Wesley Buckingham, subject of the Queen of Great Britain and Ireland, residing at London, England, have invented a new, original, and ornamental Design for a Cooking Stove, of which the following is a specification, reference being had to the accompanying drawing, forming part thereof.

Figure 1 is a front perspective view of a cooking stove showing my new design.

Figure 2 is a rear perspective view thereof.

I claim:

The ornamental design for a cooking stove, substantially as shown.
